United States Patent Office

Des. 217,533
Patented May 12, 1970

217,533

SLIPPER OR SIMILAR ARTICLE

Martin Sherman, Far Rockaway, N.Y.
(35 Claver Place, Brooklyn, N.Y. 11238)

Original design application Mar. 20, 1967, Ser. No. 6,302, now Patent No. 211,556, dated July 2, 1968. Divided and this application June 20, 1968, Ser. No. 17,144

Term of patent 7 years

Int. Cl. D2—04

U.S. Cl. D2—279

FIG. 1 is a front and side perspective view of a slipper or similar article, embodying my new design.

FIG. 2 is a top plan view thereof.

FIG. 3 is a side elevational view thereof.

FIG. 4 is a front elevational view thereof.

FIG. 5 is a rear elevational view thereof.

This is a division of copending application Ser. No. D. 6,302, filed Mar. 20, 1967, patented July 2, 1968, Pat. No. D. 211,556.

I claim:

The ornamental design for slipper or similar article, substantially as shown and described.
